CLOSURE

Carl Edward Voke, Columbus, Ohio

Application January 18, 1936, Serial No. 59,721

6 Claims. (Cl. 221—60)

My invention relates to closures. It has to do, more particularly, with a closure device which is applicable for use with containers of the collapsible type, such as those used for tooth-paste, shaving creams, ointments and similar products, although it is not necessarily limited thereto.

The most common type of closures which are now in use on containers of the type indicated comprises a cap which is adapted to be threaded on the upper end of such containers. To open the container, it is necessary to wholly remove the cap therefrom. In many instances, the cap is dropped and sometimes lost or is not replaced and the contents of the container are left open to the air, which may tend to dry, may collect dust or other impurities or may seep out of the container.

There are many types of closures which have been produced in an attempt to overcome such conditions. Most of the closures consist of some form of cap which is anchored to the tube in some manner so that it may be slipped off and on the upper end of the tube, but will still be attached to the tube. However, most of the devices have been extremely complicated, unsanitary and have been expensive to manufacture. Most of them cannot be applied to the common type of container. For these and other reasons, they have not been very widely used.

Another form of the devices which have been produced in an attempt to overcome such conditions comprises an especially made tube having a closure built in the upper end of the container. Such devices also have been too expensive to be suitable for common usage and also have other undesirable features.

Another form of devices which have been produced in an attempt to replace the commonly used screw cap are automatic closures. The majority of closures of this type have not been practical, are extremely expensive for manufacture, unsanitary and have many other prohibitive features.

One of the objects of my invention is to produce and provide a closure for containers of the type indicated which is extremely simple and inexpensive to manufacture.

Another object of my invention is to provide a closure for containers of the type indicated which will automatically open when pressure is applied to the container and which will automatically close when pressure is removed.

Another object of my invention is to provide a closure for containers of the type indicated which can be made as a separate unit from the container

and which may be applied to any common form of container of the type indicated which is now in general use.

Another object of my invention is to provide an automatic closure for containers of the type indicated which has a minimum number of parts.

Another object of my invention is to provide an automatic closure of the type indicated which is sanitary and has no crevices or holes on its outer surfaces for material to collect or dry.

Another object of my invention is to provide an automatic closure which is air-tight when it is not in operation.

Another object of my invention is to provide an automatic closure for containers of the type indicated which may easily and successfully be dipped in gelatin or other similar sealing compounds as a double protection against the seepage of glycerin and other similar substances over long periods of time under different temperatures.

In its preferred form, my invention contemplates the provision of a closure which is automatically operative to open or close the upper end of the container. This closure preferably comprises a cylinder which acts as a plunger and which is mounted in the neck of the container in such a manner that it is freely slidable therein. This cylinder is provided with a closed lower end and a closed upper end. A groove is provided in the out-side periphery of the cylinder from its lower end to near the top end. A spring is mounted in surrounding relation to the cylinder at its lower end and is adapted to return the cylinder to its original position after pressure which has caused it to move upwardly has been released.

The preferred embodiment of my invention is shown in the accompanying drawing wherein similar characters of reference designate corresponding parts and wherein:

Figure 1 shows a cross section view of the upper end of the container with the plunger and spring in position for assemblage.

Figure 2 shows a cross section view of the upper end of the container with the plunger, spring and collar in position for assemblage as a complete unit independently from the container.

Figure 3 shows an assembled view of the closure in operation in the neck of the container.

Figure 4 shows a cross section view of the plunger, shell and spring in position for assemblage as an independent closure to be attached to the neck of the container.

With reference to the drawing, my closure device comprises a cylinder 6 which acts as a plunger which is of slightly less diameter than that of

the inner periphery 3 of the neck 2 of the container 1 and which is adapted to fit freely therein. This cylinder 6 is solid in its preferred form and comprises a closed lower end 9 which may be either flat or rounded, a closed upper end 7 which may also be flat, rounded or of any other desirable shape, a slight flange 8 being formed near the top of the cylinder. The flange 8 will seat on the top edge 14 of the neck of the container when the cylinder 6 is in its lowermost position. A groove 10 is formed near the lower end of cylinder 6. The lower end of spring 13 will fit in this groove 10. It is understood that a flange may be formed on the base 15 of cylinder 6 instead of groove 10 or any other suitable means used to hold the spring 13 in surrounding relation to the cylinder. A dispensing slot 11 is formed on one side of the cylinder 6 from the lower end 9 nearly to the flange 20 8. It will be readily seen from Figure 1 that the cylinder 6 will be freely slideable within the inner periphery 3 of the neck of the container. Spring 13 will fit in surrounding relation to the cylinder 6 with the top part of the spring abutting against the upper part of the indenture 4 formed in the neck of the container and the lower part of the spring fitting into the groove 10 of the cylinder. It will be understood that when the cylinder 6 is forced upwardly, the spring 13 will compress and as soon as the pressure is released which caused the cylinder to move upwardly, the spring will again expand and return the cylinder to its original position.

When in operation, the cylinder 6 will reach 35 its uppermost position as shown in Figure 3.

When it is desired to dispense material from the container, pressure is applied to the body portion of the container which causes the material therein to move upwardly into the dispensing slot 11 and will exert a force on the top wall of the dispensing slot. This will cause the cylinder 6 to move upwardly against the force of the spring. When the cylinder moves upwardly, the upper part of the dispensing slot 40 moves away from the top 14 of the neck of the container and will allow the material to be dispensed through the opening formed. As soon as the pressure that caused the container to collapse has been removed, the spring 13 will cause 50 the cylinder 6 to return to its original position and seat on the upper part of the neck 4.

Figure 2 shows a slightly modified form of my automatic closure. The cylinder 6 and spring 13 correspond exactly with the description given 55 above regarding Figure 1. A small collar 28 is added to this modified form. This collar has an open upper end 18 and an open lower end 17. The cylinder 6 is adapted to fit within the inner periphery of the collar so that it will be 60 freely slideable therein. The lower outside periphery of the collar 28 is adapted to fit friction tight within the neck 27 of the container 1. In as much as the containers of the type indicated are usually made of soft metal, it is understood 65 that a friction tight fit is practical and sufficient to hold the closure in place. However, if desired, it is understood that the outer periphery of the lower part of the collar may be threaded so that it may be screwed into the neck of the container or that a groove may be formed in the outer wall of the collar 28 so that the metal of the neck of the container may be pressed into the said groove to hold the collar sufficiently in 70 place, or any other satisfactory means may be

employed to fasten the collar in the neck of the container.

Near the upper part of the collar, a flange 15 is formed and is so adapted that its lower part 16 will rest on the top portion 14 of the neck 5 27 of the container. The flange 15 on the collar is so shaped in relation to the neck and the top 7 of the cylinder that there are no exposed crevices or spaces for material to collect, dry or become unsanitary. 10

In assembled form, it will be readily seen that the cylinder 6 will fit into the collar so that the flange 8 will rest on the top edge 19 of the collar. The top part of spring 13 will abut against the lowest portion of the collar and the bottom 15 part of the spring will rest in the groove 10 formed in the cylinder. The assembled closure is pressed into the neck of the container so that the bottom of flange 16 will rest on the top part 14 of the neck of the container. In operation, 20 the cylinder 6 will move upwardly from the collar, compressing the spring and allow the material to be dispensed from the discharge slot 11. When the pressure is released which caused the cylinder to move upwardly, the spring will expand, 25 forcing the cylinder to return to its original position so that the upper part of the flange 8 will rest on the top 19 of the collar. In reference to Figure 2, it will be readily apparent that this modified form closure may be completely assembled independently from the container and then fastened in the neck of any container now in common use and would also eliminate the process now used in threading the outer walls of 30 the neck. 35

In reference to Figure 4, I have shown another slightly modified form of my closure. The cylinder 6 and spring 13 again correspond to the description above stated in relation to both Figure 1 and Figure 2. Instead of the cylinder being 40 placed in the neck of the container and in the collar, in this form it is placed in the upper end of a shell 20 in the same manner. In reference to the drawing, this shell comprises an open lower end 26 and an open upper end 22. The 45 opening in the upper end of the shell is of slightly greater diameter than the body portion of the cylinder so that it is freely slideable therein in relation to the inner periphery 24. The opening 26 in the base of the shell is of greater diameter than opening 22 and is extended upwardly to form a ledge 25. In the lower wall of the shell, threads are formed so that it may be attached to any of the common forms of containers of the type indicated. However, although threads 50 are shown as the manner for attaching the shell to the container, it is understood that any other suitable means may be employed. 55

In assembling, the cylinder 6 fits in the upper end of the shell 20 so that the flange 8 seats on 60 the top edge 23 of the shell. The top part of spring 13 abuts against the ledge 25 of the shell and the base of the spring fits in the groove 10 of the cylinder. In operation, this modified form of closure operates in the same manner as described above regarding Figure 1 and Figure 2. 65

It will be readily seen from this description above that I have produced a novel form of closure device which may be easily attached to any of the common forms of containers of the type 70 indicated. It will be seen further that this device is of such a character that the entire contents may be dispensed therefrom. It will also be seen that this device is automatically operative to allow the material to be dispensed from 75

the container and to automatically seal said container. It may also be seen that this device may be made as a permanent part of the container or may be made entirely as a separate unit. It will be seen further that this device is very simple, inexpensive to manufacture and easily applied to the form of container of the type indicated. It can be seen further that the device is sanitary while in use.

Having thus described my invention, what I claim is:—

1. In combination, a collapsible tube having a neck, said neck having an opening with walls of uniform diameter, a plunger slidably fitted within said neck, an indenture formed within the lower part of said neck, said plunger having a flange formed near its upper end to seat on the top edge of said neck when the plunger is in its lowermost position, said plunger having a vertical groove in its outer wall, the top of said groove serving as a discharge opening when the plunger is in its uppermost position, and a spring confined between the base of said plunger and said indenture, said spring serving to automatically 25 return the plunger to and maintain it in its lowermost position for closing the tube.

2. A closure for collapsible tubes and the like, comprising a plunger having a solid top and bottom, a ring in which said plunger is slidably fitted, said ring having a flange formed on its upper outside periphery, means for yieldingly holding said plunger in its lowermost and normal position and for returning said plunger to said lowermost position after pressure on the tube which caused it to move upwardly has been released, the closure being made and assembled independently from the tube and adapted to fit in the neck portion of the tube.

3. A closure for collapsible tubes and the like, comprising a plunger having a solid top and base, a flange formed near the upper end of said plunger, a collar in which the plunger is slidably fitted, said collar having a flange formed near the top of its outer surface, said flange being adapted to rest on the top edge of the neck of an associated tube, the lower outer surface of said collar being adapted to fit tightly within the neck of the tube, said plunger having a vertical slot in its outer surface extending from the base to a position substantially adjacent to the said flange on its top, said slot serving as a discharge opening when the top thereof is disposed above the top of said collar, an indenture formed with said plunger adjacent to its base, and a spring seated 55 at its lower end on said indenture, the top of said spring abutting against the lower surface of

said collar, the entire closure being made and assembled independently from the tube.

4. A closure for collapsible tubes and the like, comprising a solid cylinder having the upper end thereof provided with a cap flange, said cylinder having a vertical groove formed in its outer surface and extending from its base to a position immediately adjacent to the cap flange, a ring in which said cylinder is slidably fitted, the cap flange of said cylinder resting on the top of said ring when said cylinder occupies its normal and lowermost position, means for holding said cylinder in its lowermost position when not in use and to return said cylinder to its lowermost position after use, the said ring being adapted to fit tightly within the neck of an associated tube and said closure being made and assembled independently of the tube.

5. An automatically operative closure for collapsible tubes, comprising a solid plunger having a cap flange formed on its upper end, a hollow shell in the upper end of which said plunger is slidably fitted, said flange resting on the top edge of said shell when the plunger is in its lowermost position, means for yieldingly holding said plunger in its lowermost position when not in use and to return said plunger to its lowermost position after being forced upwardly by pressure, said shell being adapted for attachment to the neck of an associated tube and said closure being made and assembled independently from the tube.

6. An automatically operative closure for collapsible tubes and the like, comprising, in combination, a solid cylinder formed with a cap flange near its upper end, a hollow shell in the upper end of which said cylinder is slidably fitted, the base of said flange resting on the top edge of said shell when said cylinder is in its normal and lowermost position, said cylinder having a vertical groove extending from said base substantially to said flange, there being a second groove formed in said cylinder around the base thereof, a spring having its lower end seated in said last-named groove and having the upper end thereof disposed to abut against the under surface of the top of said shell, said spring normally serving to hold said cylinder in its lowermost position and to return said cylinder to its lowermost position after it has been forced upwardly by pressure on an associated tube, said shell being formed for attachment to the neck of the tube, and said closure as a whole being made and assembled independently from the tube.

CARL EDWARD VOKE.
